DESIGN FOR A CYCLIST HANDLE GRIP

Donald Robert Black, Chicago, Ill., assignor to
Inland Rubber Corporation, Chicago, Ill., a cor-
poration of Illinois

Application July 26, 1945, Serial No. 120,981

Term of patent 14 years

(Cl. D90—11)

To all whom it may concern:

Be it known that I, Donald Robert Black, a citizen of the United States, residing at Chicago, in the county of Cook and State of Illinois, have invented a new, original, and ornamental Design for Cyclist Handle Grips, of which the following is a specification, reference being had to the accompanying drawing, forming a part thereof.

Figure 1 is a top plan view of a cyclist handle grip, showing my new design;

Figure 2 is a left side elevational view;
Figure 3 is a right side elevational view;
Figure 4 is a bottom plan view;
Figure 5 is a rear end elevational view; and
Figure 6 is a front end elevational view thereof.

I claim:

The ornamental design for a cyclist handle grip, as shown.

DONALD ROBERT BLACK.
